UNITED STATES PATENT OFFICE.

CHRISTIAN E. HANSEN, OF CHICAGO, ILLINOIS.

PROPELLER FOR VESSELS.

SPECIFICATION forming part of Letters Patent No. 643,646, dated February 20, 1900.

Application filed July 20, 1899. Serial No. 724,470. (No model.)

To all whom it may concern:

Be it known that I, CHRISTIAN E. HANSEN, a citizen of the United States, residing at Chicago, in the county of Cook and State of Illinois, have invented certain new and useful Improvements in Propellers for Steam and other Vessels, of which the following is a full, clear, and exact specification.

This invention relates to propellers for steam and other vessels in which the paddles are secured to an endless traveler propelled by drums in turn actuated by steam or any other power.

One object of my invention is to have a propeller of such a construction and arrangement that it may be located on each side of a boat in such a manner that only about one-half of the paddles are in the water at the same time, which paddles may be actuated by a shaft movement having a uniform motion, as distinguished from a crank-arm movement common to most vessel paddle-wheels, and so secured to an endless traveler as to reduce the leverage tending to bend them out of their proper position or with relation to the traveler.

A still further object is to provide a simple and effective construction preventing the paddles from accidentally engaging with the drums carrying the cables or other endless carrier to which the paddles are secured.

With these ends in view my invention consists in certain features of novelty in the construction, combination, and arrangement of parts by which the said objects and certain other objects hereinafter appearing are attained, all as fully described with reference to the accompanying drawings, and more particularly pointed out in the claim.

In the said drawings, Figure 1 is a side elevation of a boat, illustrating the operative position of a propeller containing my invention. Fig. 2 is an enlarged side elevation of a propeller alone. Fig. 3 is an end elevation of the same. Fig. 4 is a detail section taken transversely of the cable or other carrier, illustrating means for securing paddles thereto; and Fig. 5 is a side elevation of the same.

A indicates a boat of any ordinary construction having projecting from its sides two shafts B C, which may be propelled by steam or hand power, depending upon the character of boat in which they are used. The shafts

B C have secured thereon grooved drums D E, with space between them corresponding with the width of the paddles F.

The paddles F are secured to cables G G at each side in such a manner that a portion of the bodies of the paddles may project between the said drums, and by reason of this I am enabled to secure the paddles to the cables at about midway their lengths, the purpose of which is that when in the water the pressure thereof will be equally distributed both above and below the cable and on the paddles in such a manner that the paddles will remain upright in the water and the line of the water-pressure be at all times parallel with the cables and the strain of the paddles upon their fastenings to the cables be reduced to the minimum.

As shown in Fig. 2, the paddles are secured to the cables by laterally-projecting plates a, clamping the cable, and bolted together by bolts (indicated at b) on each side of the cable, the equivalent of which plates, as shown in Fig. 4, has an arm c, secured by a bolt d to the paddles at each side thereof and bent upon the cable and clamped by means of the bolts or rivets e.

To prevent the submerging of the paddles in their upper and forward movement when from any cause the vessel careens, the upper paddles are inclosed by a casing H, extending over the paddles and well down upon the outer sides thereof to as nearly as practical the lower and operating paddles, as shown in Fig. 1.

Having thus described my invention, what I claim as new therein, and desire to secure by Letters Patent, is—

The combination with a vessel, of an endless paddle-propelling device arranged upon the outer sides thereof and comprising parallel cables, paddles rigidly secured to said cables at a right angle thereto and projecting beyond both sides of the cables, grooved drums carrying said cables and between which the paddles project, shafts actuating said drums and a casing inclosing the upper paddles, substantially as described.

CHRISTIAN E. HANSEN.
